DESIGN FOR A SHAVING STICK CONTAINER OR SIMILAR ARTICLE

Raymond Loewy, New York, N. Y., assignor to Parfums Schiaparelli, Inc., New York, N. Y., a corporation of New York

Application June 12, 1940, Serial No. 92,946

Term of patent 14 years

To all whom it may concern:

Be it known that I, Raymond Loewy, a citizen of United States of America, residing at New York city, in the county of New York and State of New York, have invented a new, original, and ornamental Design for a Shaving Stick Container or Similar Article, of which the following is a specification, reference being had to the accompanying drawing, forming part thereof.

In the drawing

Fig. 1 is a perspective view of a shaving stick container, showing my new design, and Fig. 2 is a top plan view thereof.

I claim:

The ornamental design for a shaving stick container or similar article, substantially as shown.

RAYMOND LOEWY.
